UNITED STATES PATENT OFFICE.

IRVIN M. PRIEST, OF LINCOLN, NEBRASKA.

REIN-SUPPORT.

SPECIFICATION forming part of Letters Patent No. 723,918, dated March 31, 1903.

Application filed June 27, 1902. Serial No. 113,461. (No model.)

To all whom it may concern:

Be it known that I, IRVIN M. PRIEST, a citizen of the United States, residing at Lincoln, in the county of Lancaster and State of Nebraska, have invented a new and useful Rein-Support, of which the following is a specification.

My invention is an improved rein-support adapted for slidably connecting a pair of driving-reins together to prevent the reins from becoming caught under the horse's tail; and it consists in the peculiar construction and combination of devices hereinafter fully set forth and claimed.

15 In the accompanying drawings, Figure 1 is a perspective view of a rein-support embodying my improvements. Fig. 2 is a longitudinal sectional view of the same. Fig. 3 is an end elevation of the same at right angles to Fig. 2. Fig. 4 is a perspective view showing my improved rein-support applied to a pair of driving-reins.

In the construction of my improved rein-support I provide a base-plate 1, the ends of which are turned outwardly at right angles and each provided with a transverse opening 2, whereby loops 3 are formed at the ends of the base-plate, through which loops one of the reins may be passed. The said base-plate is provided at its center with a projecting stud 4, which is adapted to enter an opening in the rein to secure the base-plate thereon, and by providing the rein with a number of such openings the rein-support may be adjusted 35 thereon.

An arm 5 projects from the center of the base-plate from the side opposite the loops 3, and the said arm is formed with a rein-loop 6, which is parallel with the loops 3. In practice the arm 5 and loop 6 are formed of a single strip of metal bent as shown, the end portions thereof forming the arm being in contact with each other and having studs 7 at their ends, which studs are secured in openings in the base-plate by swaging, as shown.

It will be understood that the rein which passes through the loop 6 is free to slide therein, so that the reins may be manipulated as is required in driving. The rein-support

is attached to the reins at a point above the tail of the animal and serves to slidably connect the reins together, so that the horse when switching his tail cannot catch one of the reins thereunder.

Having thus described my invention, I claim—

1. A rein-support comprising a plate provided with spaced loops, a running-loop having a shank, and a stud arranged between the spaced loops, the stud and the shank of the running-loop being engaged with adjacent openings in the plate with the shank resting on the head of the stud.

2. A rein-support comprising a plate provided with spaced loops, a running-loop having a shank, and a stud arranged between said spaced loops the stud and the shank of the running-loop being engaged with adjacent openings in the plate and being headed at the opposite surfaces thereof.

3. A rein-support comprising a plate having spaced loops and means for adjustably securing it to a rein, said plate being provided on the other side with a running-loop composed of a strip of metal bent to form a loop and having the ends thereof disposed in contact and at right angles to the loop forming a shank, said shank being provided with means for engaging said plate.

4. A rein-support comprising a base having loops at its ends and a central stud to adjustably secure the same on one rein, said loops and stud projecting from one side of the base, and an arm formed by bending and doubling a metallic strip to form a loop at the outer end thereof, the inner end of said arm comprising the end portions of said strip being formed with studs, the latter being inserted and swaged in openings with which the base is provided so that the inner end of the arm is disposed on the head of the stud.

In testimony that I claim the foregoing as my own I have hereto affixed my signature in the presence of two witnesses.

IRVIN M. PRIEST.
